HORIZONTAL BROACHING MACHINE

Oliver W. Bonnafé, Hudson, Mass., assignor to
 The Lapointe Machine Tool Company, Hudson,
 Mass., a corporation of Maine

Application November 16, 1942, Serial No. 465,779

11 Claims. (Cl. 90—33)

This invention relates to horizontal broaching machines in which a plurality of broaches are drawn simultaneously through a corresponding number of work pieces and in which the broaches are returned to initial position after the work pieces have been advanced out of broaching position.

In the operation of such a broaching machine, the leading ends of the broaches are first inserted through the work pieces and are locked to the main ram, which is thereafter actuated to pull the broaches through the work pieces for a broaching cut.

After the broaches have entirely cleared the work pieces, the work holder is advanced one-half step to bring the work pieces out of alignment with the broaches and to bring the broaches into alignment with certain intermediate return tubes.

The main ram is then reversed, pushing the broaches through the return tubes, whereupon the notched rear ends of the broaches are received and latched in a return puller slide. This slide is then withdrawn to complete the return movement of the broaches to a point where they entirely clear the work holder and the work pieces supported thereby.

The work holder is then advanced another half step to bring each work piece into alignment with the next broach in the series, after which the puller slide is given a return movement to push the leading ends of all of the broaches through the work pieces to inserted positions in the main ram. The broaches are then locked in the ram and are drawn through the work pieces for a second broaching operation.

My present invention relates particularly to the construction and operation of the return puller slide and of certain latching and locking devices associated therewith.

It is the general object of my invention to provide improved means for locking the broaches in the return puller slide prior to broach-return, and for unlocking the broaches prior to a subsequent broaching operation.

To the attainment of this general object, I provide certain improved locking devices which are simultaneously operative on any number of broaches within the capacity of the machine. I also provide improved operating mechanism for the locking devices, which mechanism is simple in construction and extremely reliable in operation and which is definitely timed in relation to the movements of the return puller slide.

My invention further relates to certain arrangements and combinations of parts which will

be hereinafter described and more particularly pointed out in the appended claims.

A preferred form of the invention is shown in the drawings, in which

Fig. 1 is a plan view of a portion of a broaching machine embodying my invention;

Fig. 2 is a partial side elevation, looking in the direction of the arrow 2 in Fig. 1;

Fig. 3 is an end elevation, looking in the direction of the arrow 3 in Fig. 1;

Fig. 4 is an enlarged end elevation of certain operating parts, looking in the direction of the arrow 4 in Figs. 1 and 5;

Fig. 5 is a sectional side elevation, taken along the line 5—5 in Figs. 1 and 4;

Fig. 6 is a sectional side elevation, taken along the line 6—6 in Fig. 1;

Fig. 7 is an enlarged sectional side elevation of the broach-holding latch and associated parts, taken along the line 7—7 in Fig. 1; and

Fig. 8 is a view similar to Fig. 7 but showing the parts in unlocked position.

That portion of the machine which supports the work while the broaches are pulled therethrough on a broaching cut is not shown in the drawings but is located at the right of the parts shown in Fig. 1 and is disclosed in full detail in my prior application, Serial No. 410,461, filed September 11, 1941.

For the purpose of this application, it is sufficient to state that a plurality of work pieces are mounted in a rotatable work holder corresponding in number of work stations to the number of puller heads in the broach-return mechanism shown in the present application. The work holder further has broach-return tubes between the work stations, and intermittently actuated feeding mechanism is provided by which the work stations and return tubes are alternately aligned

with the broaches. This work-holding and work-feeding apparatus forms no part of my present invention and is thus briefly described merely for general information as to the setting in which the present invention operates.

Referring to the drawings, I have shown portions of the fixed frame 10 of a broaching machine having inwardly projecting guideways 11 supported on the opposite side walls thereof. A return puller slide 14 is slideable in the guideways 11 and is actuated by a piston 15 (Fig. 2) movable in a fixed hydraulic cylinder 16 and having a piston rod 17. The rod 17 is connected to the puller head slide by a bushing 20 (Fig. 5), slideable in a bracket 21 projecting downward from the slide 14.

The bushing 20 is provided with a flange 22 at one end and is seated against a shoulder 23 on the piston rod 17 by a second bushing 25, pinned at 26 to the end of the piston rod and having an end flange 27. The flanges 22 and 27 are spaced to provide limited lost-motion for the bracket 21 between the flanges. On each reversal of the movement of the piston rod 17, this lost-motion must be taken up before the carriage 14 will be moved. It is this lost-motion which is utilized to operate the locking devices for the broaches in the return puller slide, as will be hereinafter described.

As the broaches B (Figs. 7 and 8) are returned through the intermediate return tubes, the notched rear end of each broach is received in a return puller head 30, having a cylindrical opening 31 to receive a rotatably mounted broach support 32 in which a latch 33 is pivoted. A spring 34 normally presses the latch against a stop pin 35 in the support 32.

Each latch 33 has a depending lug 36 adapted to enter a notch 37 near the rear end of an associated broach B. The extreme rear end of the broach is preferably beveled, as indicated at 38 in Fig. 8, so that the broach may be yieldingly inserted under the latch 33 by overcoming and compressing the spring 34.

Each latch 33 has a conical recess 40 in its rear face to receive the adjacent conical end 41 of a locking plunger 42, as shown in Fig. 7. When these plungers 42 are in advanced or operative position, the latches 33 are locked so that the corresponding broaches cannot be yieldingly removed and so that they may be drawn rearward by the return puller slide.

Preservation of the exact angular position of the broaches being important, the latch holder 32 is provided with a recess 44 (Fig. 7) to receive the end of a binding screw 45, and is also provided with a milled or knurled flange 47. A suitable hand tool may be inserted through an opening 48 to engage the flange 47 and move the support 32 angularly to a position in which the lug 36 of the latch 33 will be accurately aligned with the surface of the notch 37 in the associated broach when the broach is in the desired angular position. The opening 48 may be plugged or otherwise closed when not in use.

The return puller heads 30 are mounted on tubular supports 50 (Fig. 1), the rear ends of which supports are clamped in an annular member 51 which is mounted on a sleeve 52 (Fig. 5) which is fixed in a bracket 53 at the right-hand or forward end of the slide 14, as shown in Figs. 1 and 2. A spacing disc 55 (Figs. 1 and 6) is provided to hold the puller heads 30 in equally spaced angular relation, but the heads 30 and associated parts are otherwise entirely supported by the bracket 53 on the slide 14.

At their rear ends, the locking plungers 42 extend through openings in a ring 60 (Fig. 5) mounted on a sleeve 61 slidable on a collar 62 secured to the rear or left-hand end of the fixed sleeve 52 previously described. A spring 64 is mounted on each plunger 42 between the ring 60 and a pair of adjustable lock nuts 65. Additional lock nuts 66 on the end of the plunger may be used for accurately adjusting the plunger lengthwise.

A lever 70 is pivoted on a bearing bracket 71 fixed to the slide 14 and has a pin-and-slot connection at its upper end to a cross bar 74, which in turn is connected by draw bars or bolts 75 to the ring 60 previously described. At its

lower end, the lever 70 has a pin-and-slot connection to the bushing 25 which is fixedly mounted on the rear end of the piston rod 17.

Movement of the slide 14 to the left in Figs. 1 and 2 is limited by stop pins 77 yieldingly mounted in sockets in a frame member 78 secured to the end plate 79 of the frame 10 by a bolt 80.

Having described the details of construction of my improved return puller heads and associated parts, the operation thereof is as follows:

As the broaches B are moved rearward or to the left through their return tubes after a broaching stroke, the notched rear ends of the broaches enter the return puller heads 30 and yieldingly displace the latches 33 to reach the position shown in Fig. 8. Hydraulic pressure is then applied at the right-hand end of the cylinder 16 to force the piston 15 and piston rod 17 to the left.

The first effect of this piston rod actuation is to move the bushing 20 to the left relative to the return puller slide 14 and bracket 21 until the flange 22 positively engages the bracket 21. Such lost-motion movement of the piston rod 17 is effective through the lever 70 to simultaneously advance all of the locking plungers 42 from the position shown in Fig. 8 to the position shown in Fig. 7, in which latter position all of the latches 33 are locked in holding position.

Continued actuation of the piston 15 and piston rod 17 then exerts direct pressure through the flange 22 against the bracket 21 and slide 14, and the slide 14 is moved to the left, thus drawing the broaches B to the left beyond the work pieces and out of the return tubes to extreme left-hand or withdrawn position.

After the work pieces have been advanced to their next broaching position, pressure is reversed in the cylinder 16 and the piston 15 and piston rod 17 are moved to the right in Fig. 1. The first effect of such movement is to draw the bushing 20 freely through the bracket 21 until the flange 27 engages the bracket. This relative movement or lost-motion rocks the lever 70 to withdraw all of the plungers 42 from the locking position shown in Fig. 7 to the inoperative position shown in Fig. 8.

Continued movement of the piston 15 and piston rod 17 to the right then positively advances the bracket 21 and slide 14 and pushes the leading ends of the broaches through the work pieces and into engagement with the main ram, to which they are then secured by additional locking devices, not shown.

During this advance movement of the broaches toward the main ram, the rear ends of the broaches are still engaged by the latches 33 but the latches are not locked, so that the broaches may be yieldingly pulled out of the return puller heads as soon as the broaching operation is initiated by movement of the main ram.

The return puller heads and their associated parts then remain in the described advanced position until the broaching operation is completed and the work pieces are again moved out of broaching position. The broaches are then returned to the position shown in Fig. 8, after which the latches are again locked and the broach-return cycle is repeated, all as previously described.

From the foregoing description it will be clear that the operation of the locking plungers 42 is directly dependent on the lost-motion movement of the piston 17 relative to the bracket 21. The latches 33 are thereby locked and unlocked in

definite timed relation to the movements of the return puller slide. The latches are locked before the return movement of the slide and broaches and are unlocked just prior to the advance movement of the slide to return the broaches for connection to the main ram.

Having thus described my invention and the advantages thereof, I do not wish to be limited to the details herein disclosed, otherwise than as set forth in the claims, but what I claim is:

1. In a broaching machine, a plurality of return puller heads, broach-engaging latches in said heads, locking devices for said latches, and means to actuate all of said devices to lock all of said latches before rearward movement of the puller heads begins and to unlock all of said latches before forward movement of the puller heads begins.

2. In a broaching machine, a return puller head, a broach-engaging latch in said head, a locking device for said latch, and means to actuate said device to lock said latch before rearward movement of the puller head begins and to unlock said latch before forward movement of the puller head is completed.

3. In a broaching machine, a plurality of return puller heads, broach-engaging latches in said heads, locking devices for said latches, and means to actuate all of said devices to simultaneously lock all of said latches before rearward movement of the puller heads begins and to simultaneously unlock all of said latches before forward movement of the puller heads is completed.

4. In a broaching machine, a return puller head, a broach-engaging latch in said head, a locking device for said latch, a slide on which said puller head is mounted, hydraulic actuating mechanism for said slide including a connecting rod having provision for a definite lost-motion between said rod and said slide, and means to alternately lock and unlock said latch, said latter means being operated by said connecting rod during lost-motion of said rod relative to said slide.

5. In a broaching machine, a plurality of return puller heads, broach-engaging latches in said heads, a slide on which said puller heads are mounted, hydraulic actuating mechanism for said slide including a connecting rod, a connecting device providing a definite lost-motion between said rod and said slide, and means to lock and unlock said latches, said latter means being operated by said connecting device during lost-motion of said rod and device relative to said slide.

6. In a broaching machine, a plurality of return puller heads, broach-engaging latches in said heads, a slide on which said puller heads are mounted, hydraulic actuating mechanism for said slide including a connecting rod having provision

for a definite lost-motion between said rod and said slide, and means to simultaneously lock and to simultaneously unlock all of said latches, said latter means being operated by said connecting rod during lost-motion of said rod relative to said slide and at each end of the path of travel of said slide.

7. In a broaching machine, a plurality of return puller heads, broach-engaging latches in said heads, a slide on which said puller heads are mounted, hydraulic actuating mechanism for said slide including a connecting rod, provision for a definite lost-motion between said rod and said slide, and means to alternately lock and unlock all of said latches, said latter means being operated by said connecting rod during lost-motion of said rod relative to said slide and as said rod begins its travel in each direction.

8. In a broaching machine, a return puller head, a slide on which said head is mounted, a broach-engaging latch in said head, a locking plunger coacting with a recess in said latch to lock said latch, and means to advance said plunger to locking position as rearward travel of said slide is about to begin and to withdraw said plunger to unlocking position as forward travel of said slide is about to begin.

9. The combination in a broaching machine as set forth in claim 8, in which the locking plunger is actuated by a lever pivoted on the slide, and in which said lever is connected to an actuating rod which has a lost-motion connection to the slide.

10. In a broaching machine, a plurality of return puller heads, separate means to lock a broach in each head, a slide on which said puller heads are mounted, hydraulic actuating mechanism for said slide including a connecting rod having provision for a definite lost-motion between said rod and said slide, and actuating devices for said locking means which are operated by said connecting rod during lost-motion of said rod relative to said slide and at each end of the path of travel of said slide.

11. In a broaching machine, a plurality of return puller heads, a slide, a support on said slide on which said heads are fixed, a broach-engaging latch in each head, a locking plunger for each latch, an annular member slidable on said support and to which each locking plunger is adjustably and yieldingly connected, means to move said slide alternately rearward and forward, and means to slide said annular member on said support forward before a rearward movement of said slide and rearward before a forward movement of said slide, whereby said broaches are alternately locked and unlocked in said heads.

OLIVER W. BONNAFE.
